UNITED STATES PATENT OFFICE.

JOHN GELL, OF LONDON, ENGLAND.

AUTOMATIC TELEGRAPHIC TRANSMISSION INSTRUMENT.

No. 890,042.

Specification of Letters Patent.

Patented June 9, 1908.

Application filed August 12, 1907. Serial No. 388,233.

To all whom it may concern:

Be it known that I, JOHN GELL, a subject of the King of Great Britain, residing at London, England, have invented certain new and useful Improvements in Automatic Telegraphic Transmission Instruments, of which the following is a specification.

My invention relates to automatic telegraphic transmission devices or mechanism, and is an improvement upon the form of apparatus disclosed in Letters Patent of the United States granted to me November 13/06 #835750.

In carrying out my invention I provide a combination of main key-levers and secondary key levers at an angle thereto so that by the uniform upward and downward movement of the main key levers reversal motions are imparted to the contact device through the secondary key levers.

My object is to simplify the mechanism and render the action of the parts quick and certain.

The invention consists in the features and combination and arrangement of parts hereinafter described and particularly pointed out in the accompanying claims.

In the accompanying drawings, Figure 1 is a side elevation of so much of an automatic transmission instrument as is necessary to a clear understanding of my invention. Fig. 2 is a plan view of the main key levers of Fig. 1. Fig. 3 is a view looking from the right of Fig. 1. Fig. 4 is a detail view of parts shown in Fig. 1 showing the battery and electrical connection. Fig. 5 is a detail view of a modified form of contact device and battery and electrical connections.

In these drawings 1, 1^a are the vertically movable pins which coöperate with the perforated tape. These pins are connected pivotally at their lower ends to the main key levers 2, 2^a respectively, these main key levers being pivoted to a suitable bracket or support 3 and each having a tooth as at 4, to be acted upon by a cam device shown generally at 5. This cam device has high and low parts as shown, and it is in the form of a divided cam, one portion operating in connection with the lever 2 and the other portion, which is set at right angles to the first portion operating in connection with the tooth of the lever 2^a.

The main key levers are pressed normally upward to thereby move upwardly the pins 1, 1^a to pass through the perforations in the

tape, said upward pressure upon the main key levers being secured through springs, one of which is indicated at 6, attached to the bracket to which the main levers are pivoted and adjustable as to its pressure by a screw 7 passing through the block or bracket 8 and adapted to be locked in position by a set screw 9. By the rotary movement of the divided cam, the main key levers 2, 2^a are alternately depressed and the upward movement of these key levers, as in the patent above referred to, is controlled by the vertical pins coöperating with the perforated tape. At the rear of the main key levers steel hammer-heads 10, 10^a are arranged, said hammer-heads having faces or blocks of ivory, vulcanite or other suitable insulating material arranged therein as at 11, 11^a.

The hammer-heads are of hexagonal shape so that they may be turned to screw their shanks further into or out of the main levers 2, 2^a for purposes of adjustment, and they may be locked in adjusted position by set screws 12 passing through the split rear ends of the main lever. When the main key levers rise, owing to the absence of tape at the ends of the pins, the hammer-heads will alternately strike a contact device consisting of a key 13 of T form, which key is pivoted to a bracket or block 14, which in turn is secured to the plate 15. The vertical portion of this T shaped key depends between a pair of contact points consisting of the screws 16, 16^a adjustable through the blocks 17 secured to the face of the plate 15. The action of the hammer-heads on the horizontal arms of the T shaped contact key causes the said key to be moved with its lower end first in one direction and then in the other to alternately touch the contact points 16, 16^a. This movement of the T shaped contact key is rendered crisper and a firm contact is secured and maintained by means of a jockey roller 18 carried by a spring arm 19 which is secured adjustably to a block 20 attached to the plate 15, the adjustment of the said spring arm of the jockey roller being effected by the adjusting screw 21 passing through the arm and into the block 20 on each side of the point 22, upon which the jockey roller arm is adapted to turn slightly when adjusted by the said screws.

The key action illustrated in Fig. 3 is secured to the ebonite plate 15 which is at right angles to the plane of the main key action, the main key action being fixed to the main

front plate of the instrument and the ebonite block and secondary key action being attached to the main plate by an L shaped bracket piece. The front plate is cut through 5 to permit the right hand half of Fig. 3 to be inside of the instrument as indicated in dotted lines in Fig. 3.

A material advantage arises from the use 10 of the arrangement described which gives the hammer action by striking the secondary key action in that the action of the latter is rendered more prompt than with a reciprocating lever controlled by a crank action. I provide a check device at 23 to regulate the 15 extent of the upward movement of the pins 1, 1^a and consequently the extent of travel of the hammer devices 10, 10^a.

As will be seen from Fig. 2 the main levers 20 are of special form having their forward ends close together to be operated upon by the divided cam and their rear ends spread apart so that the hammer actions will occur at comparatively widely separated points on the horizontal arms of the T shaped contact 25 lever. It will also be observed that a special feature of my invention resides in the combination of the two actions, namely, of the main key levers and the secondary key lever at right angles to each other so that by the 30 uniform upward and downward movement of the main key levers reversal movements of the secondary key lever 13 is effected. In the post office standard pattern of transmitter this reversal movement is secured by 35 cranks and springs and my invention is an improvement upon this arrangement.

I show in Fig. 4 the electrical connections of the parts thus far described. The battery in this instance is of double form with a central earth connection. When the lower end 40 of the secondary key lever 13 moves towards the right the copper current passes to the line from the right hand side of the divided battery and the zinc current passes to earth 45 through the central connection of the battery. When, however, the T shaped key moves to the left at its lower end the zinc current passes to line and the copper to earth, and I therefore secure the reversal 50 current.

I show in Fig. 5 a modification of the secondary or T shaped key lever adapted with a single battery to give the same reversals as in Fig. 4. The key in this instance is of 55 pound form being provided with an extra contact piece 24 secured to the main portion 13 but insulated therefrom by a strip of ebonite 25. In this form I employ double contacts and a single battery to secure the reversal, these double contacts being indicated 60 at 26, 26^a and 27, 27^a, and consisting of screws adjustable through the up-turned ears or lugs on blocks or plates 28. With this arrangement when the lower end of the T 65 shape key moves towards the right the cop-

per current goes to line through the contact 27^a and the zinc current goes to earth through the contact 26, and the auxiliary portion 24 of the secondary key, this auxiliary portion closing upon the contact 26 simultaneously 70 with the closing of the main portion of the key with the contact 27^a. When the secondary T shaped key moves towards the left at its lower end the zinc current goes to line through the contact 26^a and the copper current goes to earth through the contact 27 and the auxiliary portion 24 of the secondary key lever. 75

I claim as my invention:

1. In combination in apparatus of the class 80 described a main key-action comprising the key levers pivoted intermediate of their length and arranged side by side, the pins at the ends of each of said levers operated thereby and coöperating with the perforated tape 85 and a secondary key-action arranged at an angle to the first key-action and adjacent to rear ends of said levers whereby the uniform pivotal movement of the key levers of the main key-action will effect the reversal 90 movements of the secondary key-action and contacts controlled by the secondary key-action, substantially as described.

2. In combination in apparatus of the class 95 described, a main key-action comprising a pair of key-levers arranged side by side, pins at the front ends of said levers coöperating with the perforated tape and operated by said main key-levers, and a single secondary key-lever arranged substantially at right 100 angles to the main key-levers adjacent their rear ends and operated thereby so that the uniform movement of the main key-levers in their vertical planes will effect reversal movement of the single secondary key-lever 105 and suitable contacts controlled by the said secondary key-lever, substantially as described.

3. In combination in apparatus of the class 110 described, a pair of main key-levers, a substantially T shaped secondary key-lever arranged with its head portion extending across the ends of the main lever at substantially a right angle thereto and operated thereby, pins actuated by the main key- 115 levers and coöperating with the perforated tape, and electrical contacts which are closed by the movement of the stem portion of the T shaped secondary lever, substantially as described.

4. In combination in apparatus of the class 120 described, a pair of main key-levers arranged side by side, means for operating the same, pins at the front end of said levers actuating on the tape and operated by said main key-levers, a secondary key-lever of T shape arranged substantially at a right angle to the main key-levers, electrical contacts to be closed by the stem of said T-shaped secondary key-lever, and a jockey roller and spring- 125 130

arm carrying the same for controlling the movement of the secondary key-lever, substantially as described.

5. In combination in apparatus of the class described, a pair of main key-levers, means for operating the same consisting of the cam for operating the levers one way and having an abrupt shoulder and spring means for giving the lever movement in the opposite direction, pins operated by the said main key-levers, a secondary key-action, and electrical contacts controlled thereby, the key-levers of the main key-action having a striking or hammer action upon the secondary key-action, substantially as described.

6. In combination in apparatus of the class described, the main key-levers with the pins operated thereby to co-act with the tape, means for operating the key-levers, a **T** shaped secondary key-lever arranged substantially at right angles to the main key-levers and contacts controlled by the secondary key-lever, the main key-levers having a striking or hammer-action upon the end portions of the horizontal arm of the **T** shaped secondary key-lever, substantially as described.

7. In combination in the described apparatus, the main key-levers with operating means therefor to give a hammer effect to said levers, a secondary key-action and hammer portions carried by the main key-levers for striking the secondary key-action, to give a quick action thereto, and contacts controlled by the secondary key-action, substantially as described.

8. In combination in the described apparatus, a pair of main key-levers, cams for operating the same downwardly and having abrupt shoulders, pins to coact with the tape operated thereby, means for operating said main key-levers, springs for pressing them upwardly and means for adjusting the tension of said springs, substantially as described.

45. 9. In combination with the main key-levers, a secondary key-action, means for op-

erating the main key-levers and an adjustable check for the main key-levers, substantially as described.

10. In combination with the main key-levers, a secondary key-action, and hammers carried by the main key-levers to strike the secondary key-action, said hammers comprising the pieces of insulating material and the heads adjustably connected with the main key-levers and carrying said insulating hammer pieces, substantially as described.

11. In combination in the described apparatus, a pair of main key-levers, pins to co-act with the perforated tape operated by said levers, cam means for operating the said levers one way, springs for giving a quick action to the levers the other way, said levers having their front portions in proximity to be operated by the said cam and their rear portions spread apart, a secondary key-action operated by the rear portions of the main key-levers and electrical contacts controlled by the secondary key-action, substantially as described.

12. In combination in the described apparatus, a main key-action, a secondary key-action comprising a substantially **T** shaped lever having its vertical and horizontal portions insulated from each other, a pair of contacts for each portion of the lever and circuit connections, substantially as described.

13. In combination, the key-levers of the main key-action, a secondary key-action, contacts controlled by the secondary key-action, said main levers having a hammer or striking effect upon the secondary key-action, means for operating the main levers and an adjustable check device to limit the hammering stroke of the main levers, substantially as described.

In testimony whereof, I affix my signature in presence of two witnesses.

JOHN GELL.
